UNITED STATES PATENT OFFICE.

EDWARD F. SWIGERT, OF LIMA, OHIO.

RESONATOR.

SPECIFICATION forming part of Letters Patent No. 784,082, dated March 7, 1905.

Application filed May 2, 1904. Serial No. 206,057.

To all whom it may concern:

Be it known that I, EDWARD F. SWIGERT, a citizen of the United States, residing at Lima, in the county of Allen and State of Ohio, have 5 invented certain new and useful Improvements in Resonators, of which the following is a specification.

It is customary in offices where messages of any length are received and transcribed upon 10 type-writing machines or at some distance from the receiver to locate the sounder within a box or casing having an open side and arrange said box with the open side facing the operator, so as to concentrate and direct the 15 sound-waves in a particular direction and render the message distinct above other sounds without requiring special effort on the part of the operator.

This invention provides a box which preferably 20 completely incloses the sounder, a horn being connected to the box and adjustable to admit of throwing the sound in any direction to suit the location of the operator.

For a full description of the invention and 25 the merits thereof and also to acquire a knowledge of the details of construction of the means for effecting the result reference is to be had to the following description and drawings hereto attached.

30 While the essential and characteristic features of the invention are susceptible of modification, still the preferred embodiment of the invention is illustrated in the accompanying drawings, in which—

35 Figure 1 is a perspective view of a resonator embodying the invention. Fig. 2 is a detail view of the horn and fittings, showing a portion of the box in section about on the line 2 2 of Fig. 1. Fig. 3 is a longitudinal section of 40 the fitting having direct connection with the box. Fig. 4 is a detail perspective view of the means for securing the horn at the required elevation. Fig. 5 is a view similar to Fig. 3 of the fitting to which the horn is attached.

45 Corresponding and like parts are referred to in the following description and indicated in all the views of the drawings by the same reference characters.

50 The box forming the housing or casing in

which the telegraph-sounder is located is represented at 1 and is preferably constructed of resonant material, such as wood, possessing the quality of augmenting sound-vibrations. This box or casing 1 may be of any size and 55 shape and is mounted upon feet to elevate it from the stand or table, said feet being preferably of rubber, felt, or leather, so as not to mar the surface of the table or support upon which the box may be placed. Binding-posts 60 2 are connected to the box and receive the ends of the electric conductor 3, by means of which the current is transmitted to the instrument located within the box and which instrument has the terminals of its helix connected to the 65 binding-posts 2 in any usual way. The top of the box is movable to admit of access being readily had to the interior and is held in place by suitable fastenings 4.

The means employed for connecting the 70 horn 5 to the box consist of a ring 6 and fittings 7 and 8, the latter being elbows and the several parts connected by screw-thread joints. The ring 6 is fitted in an opening in the top of the box and is supported in said opening by 75 an outer flange 9, which is apertured to receive screws or like fastenings for securing the ring in place. The lower end of the elbow-fitting 7 is threaded into the ring 6 and its upper end is internally threaded and provided with a 80 boss 10, in which is fitted a set-screw 11, the inner end of which bears against a block 12 for clamping the fitting 8 and holding it in an adjusted position after the horn 5 has been moved to the required elevation. The clamp-block 12 is fitted in a recess in the inner side of the threaded portion of the fitting 7 and is provided with a thread 13 to match and register with the thread upon the inner side of said fitting. 85

The fitting 8 is likewise of elbow form and its inner end is threaded into the upper end of the fitting 7 and its outer end has the horn 5 connected thereto. By turning the fitting 8 in the fitting 7 the outer end of the horn 5 95 may be raised or lowered, so as to throw the sound high or low as may be required according to the position of the operator. After the horn has been moved to the required position the set-screw 11 is tightened to cause 100

the clamp-block 12 to grip the inner end of the fitting 8 and hold it against movement. By turning the fitting 7 in the ring 6 the horn may be moved to any angular position about a 5 vertical axis.

Having thus described the invention, what is claimed as new is—

1. In a resonator, the combination of a box, a horn, tubular fittings connecting the horn 10 with the box, and fastening means for securing the horn when moved to the required point of adjustment, substantially as specified.
2. In a resonator, the combination of a box, an elbow-fitting connected to the box, a companion elbow-fitting connected to the first fitting and provided with a horn, and securing means between the two elbow-fittings for positively fastening them in the required adjusted position, substantially as described.
3. In a resonator, the combination of a box, a fitting connected thereto, a second fitting 15 provided with a horn and connected to the first-mentioned fitting by means of a screw-thread joint, a clamp-block applied to one of the fittings, and a set-screw coöperating with the clamp-block to secure the two fittings in an adjusted position, substantially as set forth.

4. In a resonator, the combination of a box, a fitting applied to the box and adapted to be turned about a vertical axis, a second fitting 30 connected to the first-mentioned fitting and movable about a horizontal axis, and a horn connected to said second fitting and adapted to be raised and lowered at its outer end and to be swung to any angular position about a 35 vertical axis, substantially as set forth.

5. In a resonator, the combination of a box having an opening in a side thereof, a ring fitted into said opening and having an outer flange overlapping the opening of the box and receiving fastenings, an elbow-fitting connected to the ring by a screw-thread joint, a second elbow-fitting threaded to the first-mentioned fitting, a horn attached to the outer end of the said second fitting, and securing 40 means between the two fittings for holding the horn when adjusted, substantially as set forth.

In testimony whereof I affix my signature in presence of two witnesses.

EDWARD F. SWIGERT. [L. s.]
